[57] CLAIM

The ornamental design for a jewelry chain, as shown and described.

DESCRIPTION

FIG. 1 is a top plan view of a sectional length of a jewelry chain according to the invention shown in a non-fastened, non-use position;

FIG. 2 is a bottom plan view thereof;

FIG. 3 is a first side edge elevation view thereof, the opposite side view being a mirror image; and,

FIG. 4 is a top plan view of a sectional length of the jewelry chain shown in a fastened, use configuration.
